DESIGN FOR A HANDLE FOR BUTTON-HOOKS, &c.

SPECIFICATION forming part of Design No. 29,263, dated August 23, 1898.

Application filed July 29, 1898. Serial No. 687,218. Term of patent 3½ years.

To all whom it may concern:

Be it known that I, JOSEPH E. STRAKER, Jr., of North Attleborough, in the county of Bristol and State of Massachusetts, have invented and produced a new and original Design for the Handle of a Button-Hook or Similar Article, of which the following is a specification, reference being had to the accompanying drawings, forming part thereof.

10 Figure 1 is a side view of a handle, showing my design connected with a button-hook, the blade of a paper-cutter being shown in broken lines. Fig. 2 is a cross-section of the handle on the line A A in Fig. 1.

15 The leading features of my design consist in the heart-shaped panel near the upper end of the handle, the raised scroll ornament inclosing the same surmounted by a radially-beaded ornament, and the foliated scrolls 20 extending downward over the side of the handle, terminating in two strings of beads.

In the drawings the leaved ornament 3 extends from the lower end of the handle,

and from this extends on each side of a long central bead the string of semiglobular beads 25 44, connecting with the tendrils of the foliated scrolls 5 5, overlying the bulb-shaped portion 6 of the handle. The panel 7, of heart-shaped outline, is inclosed by marginal raised beads. The foliated scrolls 8 8 extend along the edge 30 35 of the handle, and a series of semispherical beads are interspersed between the foliated scrolls 8 8 and 5 5. The handle is surmounted by the raised radially-disposed beaded crest.

Having thus described my invention, what I claim as new, and desire to secure by Letters Patent, is—

The design for the handle of a button-hook or similar article substantially as herein shown and described.

In witness whereof I have hereunto set my hand.
